UNITED STATES PATENT OFFICE.

SIGFRIED E. SUMMERFIELD, OF ST. PAUL, MINNESOTA.

DISPLAY-FIXTURE.

1,278,059.

Specification of Letters Patent. Patented Sept. 3, 1918.

Application filed October 16, 1917. Serial No. 196,777.

To all whom it may concern:

Be it known that I, SIGFRIED E. SUMMERFIELD, a citizen of the United States, residing at St. Paul, in the county of Ramsey 5 and State of Minnesota, have invented a new and useful Improvement in Display-Fixtures, of which the following is a specification.

My invention relates to display fixtures 10 which are adapted to be used in show windows in the displaying of goods and where simplicity, attractive design and neatness in appearance are primary factors.

My device is of simple construction, inexpensive to manufacture and can be used 15 as an advertising medium and at the same time display the article offered for sale.

The primary object is in a device which is formed of stampings and of a small number 20 of parts easily assembled and effective in use. It is also an object to provide a display fixture with a correctly proportioned base which holds the supporting rod so that in the displaying of goods, the device 25 will stand with firmness.

A further object is in providing a device with a pyramidal shaped base portion which is formed from a single piece of 30 thin sheet material.

In the drawing forming part of this specification:

Figure 1 is a perspective of the display device.

Fig. 2 is a plan view of the base portion 35 of the device.

Fig. 3 is a side elevation illustrating the base portion in cross section as it would appear on the line 3—3 of Fig. 2, and illustrating a portion of a shoe in displaying 40 position upon the device.

Fig. 4 is a detail of a portion of the device illustrating a portion of a lady's shoe upon the same.

Fig. 5 is a geometrical development of the 45 base portion as it would be stamped out from a flat piece of sheet material.

Fig. 6 is a perspective of a detail portion of the device.

In the drawing, A represents a display 50 device having a base portion 1 which is pyramidal in shape and which is adapted to support a rod 2. The rod 2 is formed preferably of wire and extends through the opening 3 in the apex of the base portion 1. The base portion 1 is formed from a stamping 55 from a thin sheet of material, the geo-

metrical development of the stamping being practically square. As illustrated, the base 1 is a triangular pyramid when put together, having three displaying faces 4, 5 and 6 upon which advertising matter can be stenciled or printed such as is illustrated in Fig. 1. In the formation of the base portion 1, the face 4 is formed with projecting lugs which are adapted to be inserted in the slots 8 formed along the line of the edge of the adjacent face 6 when the base 1 is bent on the dotted lines 9 as illustrated in Fig. 5. When the lugs 7 are inserted in the slots 8, they are bent or clenched over as illustrated in Figs. 2 and 3 so as to hold the base 1 in the form of a triangular pyramid, thereby giving the three display surfaces 4, 5 and 6 for advertising matter. The face 6 has a tongue portion 10 projecting therefrom which is adapted to lie against the inner surface of the face 4 when the base 1 is formed into a pyramid, thus strengthening the base along the joint and materially stiffening the base portion 1. The lower edge 11 of the tongue 10 is cut away so as to prevent the tongue from coming into engagement with the surface on which the base 1 rests when in use and, thereby, allowing easy assembling of the base. The base portion 1 is rounded off on the corners 12 so as to prevent the same from marring the surface on which the base is set and also preventing them from scratching.

The rod 2 is smaller in diameter on its lower end and is formed with a threaded portion 13 upon which the clamping nut 14 is adapted to be screwed when the rod 2 is inserted in the opening 3 and the display fixture A is put together. A shoulder 15 formed on the rod 2 is adapted to bear against the upper surface of the opening 3 in the apex of the pyramidal base portion 1, thereby allowing the clamping nut to rigidly secure the rod 2 to the base 1. When the clamping nut is tightened on the portion 13 of the rod 2, the upper edges 16 of the nut 14 are adapted to bear against the inner surfaces of the sides 5 and 6 and against the inner surface of the tongue 10, thereby stiffening the base portion 1 and forcing the tongue 10 into close engagement with the inner surface of the side 4. The nut 14 detachably holds the rod 2 and base 1 together and serves as a locking means for 110 the base portion 1 and particularly the tongue 10.

The upper portion of the rod 2 is bent so as to form a forward depending pear shaped loop 16 which in this construction, would lie at an angle to the surface on which the 5 base portion 1 of the display fixture is set. The rod 2 extends upward from the loop 16 to form a curved portion 17 and is bent from the portion 17 so as to form a depending elongated loop 18 having upper and lower 10 parallel portions 19 and 20 respectively. The loop 18 bends downward from the portion 17 and is formed so as to extend approximately at right angles to the portion 17 and the forward loop 16.

15 In assembling the display device, the loop 16 is preferably placed so as to lie in a plane directly above and centrally disposed in relation to one of the edges of the pyramidal base 1 which are formed when the base is 20 bent on the lines 9, thereby placing the loop 16 at the front of the display fixture and having the base portion extend forward under the loop 16 so as to properly balance the fixture when in use, thus the faces 4 and 5 25 would be called the front faces of the base and the face 6, the back face.

In use of the fixture A for displaying shoes, a man's shoe or other shoes with a low broad heel, is positioned as is illustrated in Fig. 3 on the loops 16 and 18 and the curved portion 17 is adapted to curve downward from the arch B of the sole of the shoe. The toe portion C of the shoe rests on the side loop 16 and the heel D extends 35 across the ends of the loop 18, thus holding the shoe in a tilted forward position so as to give a convenient position for the observer when the same is placed in a display or show window.

40 In the use of the fixture A for displaying ladies' shoes with high heels, such as E illustrated in Fig. 4, the lower surface 22 of the heel E is adapted to rest on the portion 20 of the loop 18 and the inner surface 23 of the 45 heel E is adapted to engage against the portion 19 of the loop 18, thereby, holding the shoe in a very desirable way giving a neat appearance and firmness which is not found in the use of other displaying devices.

50 The fixture A is of very simple construction being made up of a small number of parts which are easily assembled and can be easily knocked down for shipment, packing, etc., and in use, are very desirable as 55 they are properly balanced and proportioned so as to hold the shoe or article to be displayed firmly and still not using a large cumbersome device.

While I have illustrated one particular 60 form and construction of device, I desire to have it understood that the drawings are only illustrative and my device can be carried out by other means and adapted to

other uses within the scope of the following claims:

65

1. In a display fixture having a triangular pyramidal base portion formed from a single piece of thin sheet material, a supporting rod fixed in said base portion and extending upward from the apex of said base portion, said rod being formed from a single piece of wire and having its upper end bent so as to support a shoe in a displaying position.

70

2. In a device of the class described, comprising, a pyramidal base portion formed of thin sheet material, a supporting rod having its lower end rigidly fixed in said base portion and its upper end bent to form a depending pear shaped loop portion with a portion extending upward from the apex of said loop and upper and lower parallel portions being positioned at approximately right angles to said upwardly extending portion, to form a support on the upper end of said rod for the purposes specified.

75

3. In a device of the class described, comprising, a triangular pyramidal base portion formed of thin sheet material, a tongue formed integral with one of the sides of said base portion which is adapted to lie against the inner surface of the face adjacent the face carrying said tongue, to reinforce said base portion along its joint, a supporting rod extending through the apex of said pyramidal base portion and a triangular nut threaded on the end of said rod and forming a clamping means to lock said tongue in position in said base portion.

80

4. In a device of the class described having a pyramidal base portion formed of thin sheet material, a rod having supporting means formed on its upper end, an opening formed in the apex of said base portion, a shoulder formed on the lower end of said rod and a clamping nut threaded on the lower end of said rod and being adapted to hold said rod rigidly to said base portion and to hold said shoulder in engagement with the apex of said base portion.

85

5. In a device of the class described, comprising, a pyramidal base portion formed of thin sheet material, a supporting rod rigidly fixed in said base portion and formed from a single piece of material, said rod being formed with toe and heel engaging loops, said heel engaging loop being formed with a horizontal portion upon which the base of the heel of a shoe is adapted to rest and a horizontal engaging portion which is adapted to engage against the inner portion of the heel of a shoe so as to hold the shoe in a tilted forward position, substantially as described.
